CLAIM

The ornamental design for a cordless power tool housing, as shown and described.

DESCRIPTION

FIG. 1 is a right side elevational view of a cordless power tool housing showing my new design, the opposite side being a mirror;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view of a second embodiment of a cordless power tool housing, the opposite side being a mirror image thereof;

FIG. 7 is a top plan view thereof;

FIG. 8 is a bottom plan view thereof;

FIG. 9 is a front elevational view thereof;

FIG. 10 is a rear elevational view thereof;

FIG. 11 is a right side elevational view of a third embodiment of a cordless power tool housing, the opposite side being a mirror image thereof;

FIG. 12 is a top plan view thereof;

FIG. 13 is a bottom plan view thereof;

FIG. 14 is a front elevational view thereof; and,

FIG. 15 is a rear elevational view thereof.

The broken line showing of the clutch housing is for illustrative purposes only and forms no part of the claimed design.
